UNITED STATES PATENT OFFICE.

MARTIN STOFFEL, OF McHENRY, ILLINOIS.

ROAD DRAG.

Application filed October 18, 1921. Serial No. 508,521.

To all whom it may concern:

Be it known that I, MARTIN STOFFEL, a citizen of the United States, and a resident of the city of McHenry, county of McHenry, 5 and State of Illinois, have invented certain new and useful Improvements in Road Drags, of which the following is a specification.

My invention relates to new and useful 10 improvements in road drags, and has for its principal object the provision of an improved construction of this character which will be highly efficient in use.

A further object of my improved road 15 drag is the provision of a pair of co-operating diverging blades spaced apart at their inner adjacent ends to permit the passage of rocks and lumps of clay which are forced to the center of the road by the blades 20 and afterwards picked up and carted away.

Other objects will appear hereinafter.

The invention consists in the combinations and arrangements of parts hereinafter described and claimed.

25 The invention will be best understood by reference to the accompanying drawings forming a part of this specification, and in which,

Fig. 1 is a top plan view of my improved 30 road drag;

Fig. 2 is a rear elevational view of the same;

Fig. 3 is a sectional detail view taken substantially on line 3—3 of Fig. 1; and

35 Fig. 4 is a sectional detail view taken substantially on line 4—4 of Fig. 1.

The preferred form of construction as 40 illustrated in the drawings comprises a triangular shaped main frame 6 formed of an angular members 7 and 8 rigidly connected together adjacent the ends thereof to oppositely disposed diverging angular side frame members 9 and 10. Hingedly connected to the front frame member 7 and the rear 45 frame member 8, in spaced relation with respect to the side frame members 9 and 10, through the medium of suitable hinge members 9' are oppositely disposed blades 11 and 12 spaced apart at their inner adjacent ends

50 as at 13. The blades 11 and 12 when in operation are adapted to engage the surface of a road forcing loose soil, lumps of clay and rocks to the center of the road filling ruts, and holes or the like. Means is provided whereby the blades 11 and 12 are held

rigid during operation and whereby the said blades can be adjusted at any desired angle independent of each other. Said means comprises a pair of oppositely disposed levers 14 and 15 pivotally mounted on angular brace members 16 and 17 rigidly secured to the frame members 8 and 9. The lower end of each of the said levers is rigidly connected to a lug 19 which is rigidly connected to each of the blades 11 and 12. 60

Each of the said levers is adapted to engage a toothed segment 18 rigidly secured adjacent the end of each of the braces 16 and 17. Suitable latch mechanism of any approved type is provided for holding the 70 levers 14 and 15 in adjusted position with respect to the segment 18. A clevis 20 is secured adjacent each end of the frame member 7 whereby the drag may be connected to a tractor (not shown) or the like. 75

In operation as the drag is dragged over the road to be leveled, dirt, rocks, or the like will be forced to the center of the road by the diverging blades 11 and 12, filling ruts and deep holes or the like. Large 80 lumps of clay or rocks which are too large to pass into the ruts or holes are discharged through the space 13 between the inner adjacent ends of the blades.

Heretofore road drags of the character 85 herein illustrated and described comprised but a single blade which when in operation lay in a position diagonally across the road. This construction of a drag did not prove of value because the single blade when in operation and upon engagement with a wide rut would drop into the rut and dig the same deeper instead of filling it with loose dirt or the like gathered by the blade. As can be readily understood by the provision of a 90 drag as herein illustrated and described comprising a pair of oppositely disposed diverging blades, the said blades do not pass into or engage the ruts of a road no matter what size or shape they may be, as is the case 95 of the construction of a drag briefly illustrated above, but will pass over the rut discharging the dirt gathered by the blades into the same.

While I have illustrated and described the 100 preferred form of construction for carrying my invention into effect, this is capable of variation and modification without departing from the spirit of the invention. I, therefore, do not wish to be limited to the 110

2
precise details of the construction set forth, but desire to avail myself of such variations and modifications as come within the scope of the appended claim.

5 Having described my invention, what I claim as new and desire to secure by Letters Patent is:

10 A road drag including a triangularly shaped frame comprising angular front and rear frame members and opposite diverging angular side frame members, angular re-inforcing members secured to the front frame member and the side frame members, diverging blades hingedly carried by the 15 front and rear frame members, lug members

carried by the blades, an operating lever pivotally carried by each of the re-inforcing members and secured to said lugs, and a toothed segment carried by the re-inforcing members for engagement with the catch mechanism of the lever to prevent movement thereof and whereby the blades are held rigid during operation.

20 In testimony whereof I have signed my name to this specification in the presence of 25 two subscribing witnesses.

MARTIN STOFFEL.
